US0D1001096S

(12) **United States Design Patent** (10) **Patent No.:** **US D1,001,096 S**
(45) **Date of Patent:** **** Oct. 10, 2023**

(54) **HEADPHONE AND STAND ASSEMBLY**

(71) Applicant: **Guangzhou Minyuxing Technology Co., Ltd.**, Guangzhou (CN)

(72) Inventor: **Shumao Yuan**, Changning (CN)

(73) Assignee: **Guangzhou Minyuxing Technology Co., Ltd.**, Guangzhou (CN)

(**) Term: **15 Years**

(21) Appl. No.: **29/854,001**

(22) Filed: **Sep. 21, 2022**

(51) LOC (14) Cl. **14-01**

(52) U.S. Cl.

USPC **D14/206**; D14/224

(58) **Field of Classification Search**

USPC ..... D14/412-413, 432-434, 435.1, 447, D14/451-452, 457, 142, 203.8, 209.1, (Continued)

(57) **CLAIM**

The ornamental design for a headphone and stand assembly, as shown and described.

DESCRIPTION

FIG. 1 is a front perspective view of the headphone component of the headphone and stand assembly, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the headphone and stand assembly;

FIG. 9 is a front perspective view of the stand component of the headphone and stand assembly;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is an enlarged detail view of area 16 in FIG. 1;

FIG. 17 is an enlarged detail view of area 17 in FIG. 1;

FIG. 18 is an enlarged detail view of area 18 in FIG. 1;

FIG. 19 is an enlarged detail view of area 19 in FIG. 2;

FIG. 20 is an enlarged detail view of area 20 in FIG. 7; and,

FIG. 21 is an enlarged detail view of area 21 in FIG. 7;

The dot-dash broken lines delineate areas of the figures shown enlarged and form no part of the claimed design. The broken lines showing portions of the headphone and stand assembly form no part of the claimed design.

1 Claim, 21 Drawing Sheets
